UNITED STATES PATENT OFFICE

158,051

LIQUID DISPENSER

James W. Compas, South Gate, Calif.

Application June 16, 1947, Serial No. 139,702

Term of patent 3½ years

(Cl. D74—10)

To all whom it may concern:

Be it known that I, James W. Compas, a citizen of the United States, residing in South Gate, in the county of Los Angeles and State of California, have invented a new, original, and ornamental Design for a Liquid Dispenser, of which the following is a specification, reference being had to the accompanying drawings, forming a part thereof.

Fig. 1 is an elevational view of a liquid dispenser in a closed condition, showing my new design;

Fig. 2 is an end view looking in the direction of line 2—2 in Fig. 1;

Fig. 3 is a view of the opposite end of the design looking in the direction of line 3—3 of Fig. 1;

Fig. 4 is an elevational view of the design with the parts in a disassembled condition;

Fig. 5 is an end view of the dispensing end looking in the direction of line 5—5 in Fig. 5.

My design for a liquid dispenser is characterized by the specific configuration of the central portion as seen in Figure 4 of the drawing.

I claim:

The ornamental design for a liquid dispenser, as shown and described.

JAMES W. COMPAS.
